UNITED STATES PATENT OFFICE.

JOHN F. McNUTT, OF WARREN, OHIO.

DESIGN FOR A BASE OR FRAME FOR PRINTING-PRESSES.

SPECIFICATION forming part of Design No. 27,220, dated June 15, 1897.

Application filed April 23, 1897. Serial No. 633,538. Term of patent 14 years.

To all whom it may concern:

Be it known that I, JOHN F. McNUTT, of Warren, in the county of Trumbull and State of Ohio, have invented and produced a certain new and original Design for Printing-Press Bases or Frames; and I do hereby declare the following to be a full, clear, and exact description of the invention, such as will enable others skilled in the art to which it appertains to make and use the same.

This is a design for a printing-press base or frame.

In the accompanying drawings, Figure 1 is a view in side elevation. Fig. 2 is a plan view. Figs. 3 and 4 are opposite end views. Fig. 5 is a view of a modification.

Referring to the drawings, A designates an upright post or casting approximately square in cross-section and slightly tapered and curved, as at a, being flattened into a base a'. The upper end of this post or casting is flared toward the sides, as at a², and vertical

extensions a³ project upwardly parallel with each other. The top and front and rear edges of these extensions are irregular in outline. 25

With the front face of post A, near the upper end thereof, is formed a shouldered projection b, while from the rear face extends a horizontal prolongation b', the outer end of which is slightly bulged. This prolongation 30 b' may be omitted. (See Fig. 5.)

From one of the flared sides a is formed an extension of T shape.

I claim as my invention—

The design for a printing-press base or 35 frame substantially as herein shown and described.

In testimony whereof I have signed this specification in the presence of two subscribing witnesses.

JNO. F. McNUTT.
